UNITED STATES PATENT OFFICE

2,586,146

DUPLICATING MACHINE PLATE CLAMP

Herbert F. Bruns, Chicago, Ill., assignor, by mesne assignments, to Ditto, Incorporated, Chicago, Ill., a corporation of West Virginia

Application March 31, 1949, Serial No. 84,509

13 Claims. (Cl. 101—415.1)

1

The present application is a continuation-in-part of the prior application of Harold R. Gullixson and Herbert F. Bruns, Serial No. 712,538, filed November 27, 1946, and covers divisible subject matter which is the sole invention of the present applicant, although originally disclosed in said joint application.

The invention relates to a sheet or plate clamping mechanism, particularly adapted for use in association with the plate-holding segment of a duplicating machine cylinder. The invention is not confined to such use, however, as it may readily be employed with other types of machines.

The primary object of the invention is to provide clamps for the leading and trailing edges of a master sheet or plate, which effectively grip and hold the same, against any possibility of displacement in use, yet which may be quickly and easily opened and closed, for the insertion and removal of the sheets or plates.

Another object of the invention is to provide a clamping mechanism in which the jaws are maintained closed, in gripping relation to the sheet, by spring action.

Another object is to provide a clamp for one end of a master sheet or plate which is so mounted that tension is applied to the sheet, to maintain the same firmly in engagement with the adjacent surface of the cylinder.

Still another object of the invention is to provide a clamp in which the jaws are maintained closed and in which the clamp as a whole is urged in a direction to tension the sheet on the cylinder, by common spring means.

Another object of the invention is to provide improved means for opening the jaws of a plate or sheet clamp, against the action of spring means tending to close the same.

Another object is to provide, in a plate or sheet clamp, means for indenting the plate or sheet, without rupturing the same, to perform the dual functions of preventing slippage of the plate relative to the clamp and of indexing the position of the plate in the clamp, so that it may be reinserted therein, at a subsequent time, in exactly the same position, or in a slightly changed position, as desired.

Other and further objects and advantages of the invention will be apparent from a consideration of the specific embodiments of the invention, shown for purposes of illustration in the accompanying drawings, in which:

Figure 1 is a radial section through one form of head clamp and a fragmentary portion of a duplicating machine cylinder;

Figure 2 is a similar view of one form of tail clamp;

Figure 3 is a view similar to Figure 2, showing the clamp in the open position;

2

Figure 4 is a horizontal section on line 4—4 of Figure 2;

Figure 5 is an axial section on line 5—5 of Figure 2;

Figure 6 is an elevation on line 6—6 of Figure 2;

Figure 7 is a section on line 7—7 of Figure 6, showing the outer jaw and handle mechanism only;

10 Figure 8 is a similar section on line 8—8 of Figure 6;

Figure 9 is a plan view of a modified form of inner clamping plate or strip;

Figure 10 is a section similar to Figure 1, showing the modification of Figure 9;

Figure 11 is a sectional view of another form of clamping strip or plate;

Figure 12 is a sectional view of a modified form of head clamp, and

20 Figure 13 is a similar, sectional view of a tail clamp embodying the principles of the modification shown in Figure 12.

Since the invention is not limited to any particular type of printing or duplicating machine, 25 a complete machine is not shown herein, but reference is made to the above-identified joint application for a disclosure of a typical apparatus with which the clamps may be employed. Referring to Figures 1 and 2, the plate holding

30 segment 10 of a duplicating machine cylinder is provided at the leading end 11, with a radially inwardly extending flange 12 and, at the trailing end 13 with a similar flange 14. The cylinder may be of the type shown in the above mentioned

35 application, in which two segments are provided, one to hold the master plate or sheet, having the image to be reproduced disposed thereon, and the other to receive the paper sheets, to which the image is applied by the blanket roll; or the

40 cylinder may be of the type employed in two-cylinder machines, in which one cylinder carries the master plate or sheet and the other carries the paper to be printed. In either case, the surface of the cylinder is interrupted, and

45 the clamping means are secured to the circumferential end faces, in the space provided by the interruption.

As shown in Figure 1, an elongated, axially extending jaw plate 15 is provided with a plurality of radial slots 16, slidably embracing enlarged necks 17 formed on screws 18 having heads 19 on their outer ends, the screws being received in tapped bores in the flange 12. The jaw plate 15 at its upper end is turned laterally to provide a head 20 and a jaw element 21, having a downwardly and inwardly facing jaw edge 22 above a channel 23.

Surrounding the shank of each screw 18 is an apertured spacer block 25, upon which the plate 50 15 may slide in a radial plane. Inwardly of the

55

blocks 25 is a leaf 26 of a hinge 27, the leaf being appropriately apertured for the reception of the screws 18. The hinge 27 may be of the piano type and may include a pin 28 and one or more leaves 29 pivotally mounted thereon and provided with downturned ends 30, seated upon the radially inner surface of the channel 23, with the inclined portion of the leaf or leaves disposed below the jaw edge 22.

The plate 15 carries, at its ends, apertured lugs 31, to which are connected the outer ends of tension springs 32, secured at their inner ends to appropriate pins or hooks carried by the heads or spokes of the cylinder. Reference character 33 in Figure 1 represents a handle mechanism, explained in detail in connection with the tail clamp shown in Figures 2-8.

The leaf 29 constitutes a clamping strip or plate, having a pivotal connection at its opposite ends with the jaw plate and with the supporting means for the jaw plate, respectively. When the jaw plate is moved radially outwardly, against tension of springs 32, as indicated in dotted lines in Figure 1, the jaw element 21 recedes from the clamping plate 29.

The tail clamp comprises a similar jaw plate 15a, which may be identical to the plate associated with the head clamp, but simply turned around to face in the opposite direction. The plate and associated parts, in this instance, however, are mounted for swinging movement away from the end face of the flange 14 at the trailing end of the plate holding segment. An elongated hinge 35 of the piano type has an upwardly extending leaf 36 secured to the end face of the flange 14 by countersunk screws 37. To the second leaf 38 of the hinge 35 there is attached a downwardly extending leaf 39 of a second hinge 40, by means of a plurality of bolts 41, extending through registering apertures in spacer blocks 42. Nuts 43 having reduced necks disposed in the slots 16a in jaw plate 15a hold the parts together. Lock nuts 44 may be employed, if desired.

The second leaf 45 of the second hinge 40 has a downturned end 46, disposed within the channel 23a of the jaw plate, as previously explained.

Preferably, the second hinge is sectional or is constituted by a plurality (e. g. four) of independent hinges, as indicated in Figures 4 and 5. Springs 32a, connected to lugs 31a, as previously explained, tend to move the jaw plate radially inwardly to the closed position. In addition, these springs, being laterally offset from an axial plane passing through the pivot pin of hinge 35, tend to swing the clamping mechanism as a whole in a clockwise direction, to the open position of the first hinge as shown in Figure 3. The swinging movement in this direction is limited by clips 50, secured to the end faces of the cylinder and having inwardly turned ends 51 lying behind the jaw plate 15a.

One end 52 of a handle lever 53 is pivoted upon the shank of one of the nuts 43. The lever carries an inwardly projecting roller 54, lying below the lower edge of the jaw plate 15a. Between the point where the roller 54 is attached and the opposite end 55, the lever is bent outwardly as at 56, so that the latter end portion clears the adjacent screw 41 and the nuts 43 and 44 mounted thereon, as indicated in Figures 4 and 6. The last-mentioned screw 41 carries the upper end 51 of a bracket 58, having its outer or rear end 59 turned upwardly, to provide a channel or pocket for receiving the lever, for

limiting its downward movement, and for guiding the same in its swinging movements. The end 55 of the lever preferably has a laterally turned finger piece 60, by which the lever may be swung upwardly, about its other end as a fulcrum, to lift the jaw plate and to swing the hinge 35 from the open position, as indicated in Figure 3, toward the cylinder, against the tension of springs 32a, to facilitate the introduction of the trailing end P' of the master plate or sheet P. When the handle or lever is released, the springs 32a move the jaw plate inwardly to grip the master plate. Thereafter they tend to swing the jaws in a clockwise direction to apply tension to the strip or sheet on the surface of the cylinder.

It has been found desirable, particularly in the use of certain types of master plates or sheets, to provide means for indenting the plates and for tightly gripping the same at a plurality of spaced points along their leading and/or trailing edges. As shown in Figures 9 and 10, this desirable result may be accomplished by providing in the clamping strip or hinge 65, a plurality of pairs of apertures, through which wire loops 66 may be threaded, with their inner ends 67 turned up against the undersurface thereof, to secure the wires in place. The wire loops provide protuberances upon the surface of the clamping plate or strip, in closely spaced relation to the edge 22b of the jaw plate 15b. With a jaw opening proportioned as shown in Figure 10, the downturned edge of the leaf at 30 and 46 as shown in Figures 1, 2 and 3 may be eliminated, and a simple, planar leaf 65 employed.

As shown in Figure 11, the protuberances 70 may be provided, by striking upwardly, spaced portions of the metal of which the leaf or plate 71 is made.

In the form of the invention shown in Figures 12 and 13, the hinge is arranged somewhat differently, since the hinge pin is spaced from the adjacent end of the plate holding segment of the cylinder, and the free edge of the hinge projects toward, instead of away from the cylinder. Referring to the head clamp shown in Figure 12, an elongated strip or bar 78 is secured to the flange 12 of the cylinder, by any appropriate means. A plurality of spacer blocks 79 are clamped against the outer face of the strip 78, by means of bolts 80 having enlarged necks 82 and heads 81. Slidably mounted on the necks 82 are a pair of plates 83, 84, secured to each other by rivets 85 or the like, and having vertically elongated slots 86, embracing the necks 82. The outer plate 83 constitutes a jaw element and is provided at its upper edge with a laterally turned flange 87 providing a downwardly facing jaw edge. The inner plate 84 constitutes one element of a hinge, including a pin 88 and a second leaf 89. The free edge of the latter projects rearwardly and is seated upon the upper edge of the strip or bar 78. A spring 90 connected to the plates 83 and 84 urges the latter downwardly to the closed position as shown in full lines in Figure 12. A handle 91 may be mounted as previously described, to facilitate opening of the jaw. Springs 92, connected to the blocks 79 and the leaf 89 maintain the free edge of the latter upon the strip 78. When the plates 83 and 84 are raised to the dotted line position, the leaf 85 pivots on the upper edge of the strip 78, and the jaws are opened. Protuberances 66', similar to those described in connection with Figure 10 may be associated with the leaf 89.

The tail clamp shown in Figure 13 embodies

the same principle as the head clamp shown in Figure 12. Parts bearing prime numbers may be identical with those shown in Figure 12 and described above. The strip or bar 78', however, has its inner surface recessed as at 95, to accommodate the head 96 of a bolt 97, upon the outer end of which a nut 98 having a neck 99 is threaded, the nut being retained in place by a lock nut 100. Interposed between the outer face of the strip 78' and the blocks 79' is one leaf 101 of a hinge, including a pin 102, and a second leaf 103, the latter being extended upwardly into the space 95 and being secured to the flange 14 of the cylinder by countersunk screws 104. It will be readily appreciated that the entire jaw assembly may be swung rearwardly, away from the flange 14 of the plate holding segment of the cylinder, under the influence of the spring 99' and that, when a plate or master sheet is clamped between the jaws, the tendency of the spring will be to close the jaws and apply tension to the sheet.

In the clamps shown in Figures 12 and 13, outward movement of the interconnected plates 83, 84, and 83', 84' causes the jaws 87 and 87' to recede from the clamping strips 89 and 89' as the latter pivot along their inner and outer edges, on the associated hinge pins and on the upper surface of the bars or plates 78 and 78'. The hinge pins 88 and 88' are each disposed below the associated laterally projecting jaw plate while the free edge of each clamping strip or plate rests upon a surface fixed with respect to the cylinder, instead of upon a surface associated with the jaw plate. Otherwise, the action is quite similar to the embodiment shown in Figures 2-8 and 10.

The invention is not limited to the details of construction shown in the accompanying drawings and described above, but includes all modifications coming within the scope of the appended claims and their equivalents.

I claim:

1. A clamp for securing a master sheet upon the surface of a cylinder in a duplicating machine or the like, comprising an elongated plate having a laterally facing jaw, a plate support, means for mounting the plate on the support for sliding movement in its own plane in a direction transverse to its length, a clamping strip having one edge underlying said jaw and pivotally supported at that edge for movement with respect to the plate as the jaw is moved and having its other edge pivotally supported on an axis fixed with respect to the plate support, whereby the jaw recedes from the strip when moved in one direction and approaches the same in clamping relation when moved in the other direction, and means for urging the plate in the last mentioned direction.

2. A clamp for securing a master sheet upon the surface of the sheet carrying segment of a duplicating machine cylinder or the like, comprising an elongated plate extending axially of said cylinder substantially in a radial plane thereof, means for supporting the plate for limited, substantially radial, sliding movement, a jaw carried by the plate, turned laterally and having a free edge projecting toward the adjacent surface of the cylinder, a clamping strip supported by the cylinder at one edge for pivoting movement with respect thereto and supported at its opposite edge by the plate below the jaw for pivoting movement with respect thereto, whereby the strip recedes from the jaw when the plate is moved radially outwardly and approaches

the jaw when the plate is moved radially inwardly, and means maintaining the plate in the last mentioned position.

3. A clamp for securing a master sheet upon the surface of the sheet carrying segment of a duplicating machine cylinder or the like, comprising an elongated plate extending axially of said cylinder substantially in a radial plane thereof, means for supporting the plate for limited, substantially radial, sliding movement, a jaw carried by the plate, turned laterally and having a free edge projecting toward the adjacent surface of the cylinder, a clamping strip supported by the cylinder at one edge for pivoting movement with respect thereto, projecting away from the cylinder toward the jaw and supported at its opposite edge by the plate below the jaw for pivoting movement with respect thereto, whereby the strip recedes from the jaw when the plate is moved radially outwardly and approaches the jaw when the plate is moved radially inwardly and resilient means urging the plate inwardly.

4. A clamp for securing a master sheet upon the surface of the sheet carrying segment of a duplicating machine cylinder or the like, comprising a member carried by said cylinder adjacent an end of said segment and restrained against radial movement with respect thereto, an elongated jaw member extending axially of the cylinder having a laterally facing undercut jaw element projecting toward the adjacent end of the segment, said jaw member being connected to the first-mentioned member for limited substantially radial movement relative thereto, a clamping strip pivotally supported at one edge by the first-mentioned member, projecting away from the adjacent end of the segment and supported at the other edge by the jaw member and underlying said surface, whereby, when the jaw member is projected outwardly, said surface recedes from the strip and, when moved inwardly, approaches said strip in clamping relation, and means for maintaining the jaw member in the inwardly moved position.

5. A clamp for securing a master sheet upon the surface of the sheet carrying segment of a duplicating machine cylinder or the like, comprising a member carried by said cylinder adjacent an end of said segment and restrained against radial movement with respect thereto, an elongated jaw member extending axially of the cylinder having a laterally facing undercut jaw element projecting toward the adjacent end of the segment, said jaw member being connected to the first-mentioned member for limited substantially radial movement relative thereto, and a clamping strip underlying the jaw element and hingedly connected to one of said members with its opposite edge disposed upon the other member for pivoting movement with respect thereto, whereby, when the jaw member is projected outwardly, said jaw element recedes from the strip and, when moved inwardly, approaches said strip in clamping relation, and means for maintaining the jaw member in the inwardly moved position.

6. A clamp for securing a master sheet upon the surface of the sheet carrying segment of a duplicating machine cylinder or the like, comprising a member carried by said cylinder adjacent an end of said segment and restrained against radial movement with respect thereto, an elongated jaw member extending axially of the cylinder having a laterally facing undercut jaw element projecting toward the adjacent end of

the segment, said jaw member being connected to the first-mentioned member for limited substantially radial movement relative thereto, a hinge having one leaf connected to one of said members and another leaf extending laterally toward the other member and supported thereby for pivoting movement with respect thereto, the last-mentioned leaf having a portion underlying the jaw element, whereby, when the jaw member is moved outwardly, said jaw element recedes from the last-mentioned leaf and approaches the same when moved inwardly, and means for urging the jaw member inwardly.

7. A clamp for securing a master sheet upon the surface of the sheet carrying segment of a duplicating machine cylinder or the like, comprising a member carried by said cylinder adjacent an end of said segment and restrained against radial movement with respect thereto, an elongated jaw member extending axially of the cylinder having a laterally facing undercut jaw element projecting toward the adjacent end of the segment, said jaw member being connected to the first-mentioned member for limited substantially radial movement relative thereto, an elongated hinge having one leaf connected to the first-mentioned member and another leaf projecting laterally therefrom, below said jaw element with its free end pivotally supported upon the jaw member, whereby, when the jaw member is projected outwardly, said element recedes from the strip and, when moved inwardly, approaches said strip in clamping relation, and means for maintaining the jaw member in the inwardly moved position.

8. A clamp for securing a master sheet upon the surface of the sheet carrying segment of a duplicating machine cylinder or the like, comprising a member carried by said cylinder adjacent an end of said segment and restrained against radial movement with respect thereto, an elongated jaw member extending axially of the cylinder having a laterally facing undercut jaw element projecting toward the adjacent end of the segment, said jaw member being connected to the first-mentioned member for limited substantially radial movement relative thereto, an elongated hinge having one leaf secured to the jaw member below said jaw element and the other leaf projecting laterally toward the first-mentioned member and having its free edge pivotally supported thereon, whereby, when the jaw member is projected outwardly, said element recedes from the strip and, when moved inwardly, approaches said strip in clamping relation, and means for maintaining the jaw member in the inwardly moved position.

9. A clamp for securing a master sheet upon the surface of an interrupted cylinder of a duplicating machine or the like, comprising an axially extending hinge having one leaf secured to a circumferential end portion of the cylinder adjacent the interruption therein and a second leaf extending outwardly from the connection with the first leaf, a sheet clamping jaw plate supported by the second leaf for limited radial movement with respect thereto, said plate having a laterally and downwardly facing jaw surface, and a second jaw plate underlying said surface, pivotally connected at one edge to a part fixed with respect to the second leaf and at the other edge to said jaw plate, whereby outward radial movement of the first jaw plate causes the jaw surface to recede from the second jaw plate and inward movement thereof brings the same together, and

spring means for urging the first jaw plate inwardly and for swinging the second leaf away from said end of the cylinder to clamp a master sheet in the jaws and to tension the same upon the surface of the cylinder.

10. A clamp for securing a master sheet upon the surface of an interrupted cylinder of a duplicating machine or the like, comprising an axially extending hinge having one leaf secured to a circumferential end portion of the cylinder adjacent the interruption therein and a second leaf extending outwardly from the connection with the first leaf, a sheet clamping jaw plate having a laterally projecting jaw supported by the second leaf for limited radial movement with respect thereto, a third hinge leaf operatively connected to the second hinge leaf and underlying the jaw and constituting a second jaw element, whereby outward movement of the plate causes the jaws to separate and inward movement thereof causes the jaws to close, and means for urging the plate and first jaw inwardly and for swinging the second leaf away from said end of the cylinder to tension a master sheet on said surface.

11. A clamp for securing a master sheet upon the surface of an interrupted cylinder in a duplicating machine or the like, comprising an elongated, axially extending plate disposed substantially on a radial plane of the cylinder inwardly of the surface thereof within the interrupted portion, means for supporting the plate for limited substantially radial, sliding movement, a jaw carried by the plate projecting laterally toward the adjacent surface of the cylinder, restrained against inward, radial, sliding movement, a clamping surface supported by the cylinder and underlying the jaw, spring means for urging the jaw inwardly to clamp an inserted sheet upon said surface and means for moving the jaw outwardly against the force of said spring means, the last-mentioned means comprising a lever pivoted to a part fixed with respect to the cylinder for movement in a substantially radial plane, connected to the plate and having a free end arranged for manual manipulation.

12. A clamp for securing a master sheet upon the surface of an interrupted cylinder in a duplicating machine or the like, comprising an elongated, axially extending plate disposed substantially on a radial plane of the cylinder inwardly of the surface thereof within the interrupted portion, means for supporting the plate for limited substantially radial, sliding movement, a jaw carried by the plate projecting laterally toward the adjacent surface of the cylinder, a clamping surface supported by the cylinder restrained against inward, radial, sliding movement and underlying the jaw, spring means for urging the jaw inwardly to clamp an inserted sheet upon said surface and a lever for moving the plate and jaw outwardly against the force of the spring means, said lever being pivotally connected to the plate supporting means for movement in a substantially radial plane, having a portion underlying and engaging the plate and having a free end arranged for manual manipulation.

13. A clamp for securing a master sheet upon the surface of an interrupted cylinder in a duplicating machine or the like, comprising an elongated, axially extending plate disposed substantially on a radial plane of the cylinder inwardly of the surface thereof within the interrupted portion, means for supporting the plate for limited substantially radial, sliding movement, a jaw carried by the plate projecting laterally

toward the adjacent surface of the cylinder, a clamping surface supported by the cylinder restrained against inward, radial sliding movement and underlying the jaw, spring means for urging the jaw inwardly to clamp an inserted sheet upon said surface, and a lever for moving the plate and jaw outwardly against the force of the last-mentioned means, said lever being pivoted at one end to the plate supporting means for movement in a substantially radial plane, having an intermediate part underlying the plate and having its other end shaped to facilitate outward swinging movement thereof.
